Primary Examiner — Manpreet S Matharu*Assistant Examiner* — Keith J Wilson(74) *Attorney, Agent, or Firm* — Steven E. Jedlinski; Jeffrey T. Placker; Holland & Knight LLP(57) **CLAIM**

The ornamental design for a pressure washer spray gun, as shown and described.

DESCRIPTION

FIG. 1 is a top-front-right perspective view of a pressure washer spray gun;

FIG. 2 is a bottom-rear-right perspective view thereof;

FIG. 3 is a bottom-front-left perspective view thereof;

FIG. 4 is a bottom-rear-left perspective view thereof;

FIG. 5 is a front elevation view thereof;

FIG. 6 is a rear elevation view thereof;

FIG. 7 is a left elevation view thereof;

FIG. 8 is a right elevation view thereof;

FIG. 9 is top plan view thereof; and,

FIG. 10 is a bottom plan view thereof.

The broken lines are included for the purpose of illustrating portions of the pressure washer spray gun that form no part of the claimed design.

1 Claim, 8 Drawing Sheets(56)
